HAIRPIN DEVICE

Devona A. Brunner, Chicago, Ill., assignor of one-half to Howard Brunner, Chicago, Ill.

Application June 13, 1947, Serial No. 754,531

2 Claims. (Cl. 132—1)

1

This invention relates to a receptacle for the storage of "bobby" pins.

Bobby pins, that is, pins of the type shown in the attached drawing, are used very extensively for putting up curls and before each is used it must be spread open, again the rather strong spring pressure which is incorporated in these pins. However, nothing is sold along with the bobby pins to facilitate the task of opening them and accordingly women have resorted to many expedients in the opening of these pins. For example, it is a well known fact that many women open these pins with their teeth, a practice which is undoubtedly harmful to the enamel of the teeth. Others open the bobby pins with their finger nails, and find that if the finger nails are covered with any of the lacquer polishes now commonly used these polishes are chipped off by the operation of opening the bobby pin.

The present invention aims to provide a receptacle which has a plurality of pockets in which bobby pins may be placed in upright position ready for convenient use and the invention further provides a funnel which serves a dual purpose of assisting in placing the bobby pins in the pockets, and also of spreading the bobby pins before they are inserted in the hair.

One of the objects, therefore, of the invention is to provide a bobby pin receptacle having a plurality of pockets and a funnel which may be moved from one to another of the pockets.

Another object of the invention is to provide a bobby pin receptacle having a plurality of pockets and a funnel for feeding the pins into the receptacle, and which funnel serves also as a spreader for the bobby pins.

Another object of this invention is to provide a receptacle for bobby pins having a plurality of pockets for receiving and storing the pins in upright position. The pockets also serve for firmly supporting a device which may be used for spreading the bobby pins and also for funneling them into the pockets.

Other objects and advantages of the invention will become apparent from the disclosures in the specification and the accompanying drawing.

On the drawing:

Figure 1 is a top plan view of a device made in accordance with this invention;

Figure 2 is a central longitudinal sectional view of the device shown in Figure 1, showing some bobby pins contained in the receptacles;

Figure 3 is a sectional view showing the funnel and spreader member spaced apart from one of the pockets; and

Figure 4 is a sectional view showing how the funnel member is employed for spreading bobby pins.

In the drawings the numeral 10 represents generally a block of material having a flat base 11 and a plurality of pockets 12, 13, 14 and 15. The height of these pockets is preferably less than the length of the bobby pins which are currently sold, and all of which appear to have the same length. Accordingly the height of the pocket will be such that when a bobby pin such as 16 protrudes therefrom enough of it will protrude to be readily grasped by the fingers of the user.

The device should contain at least two and preferably more pockets, so that when one pocket has been adequately filled with bobby pins, fed thereto through the funnel, the funnel may be moved to another pocket after which the contents of the first mentioned pocket are readily available for use.

A funnel shaped device 17 is provided and so proportioned that its lower portion 18 may be seated fairly snugly in any of the pockets whereby the funnel will be held against rocking movement.

It is apparent that the funnel serves the usual purpose of a funnel in making it easy to drop the bobby pins into any selected pocket. Furthermore, the edge of the funnel affords a needed device for spreading the bobby pins. It is found that they may be pressed downwardly so that the straight leg 19 of one of these pins will pass beyond and below the edge of the funnel while the lower end of the wrinkled leg 20 will engage the inner edge surface of the funnel and thereby be spread or deflected as the bobby pin is pressed vertically downwardly.

By rocking the pin as indicated in Figure 4 a further spread of the two legs of the pin may be obtained.

While it will be readily apparent that the use of a spreader of this character is a considerable improvement over the use of the finger nails or teeth for spreading the bobby pins, attention is called further to the fact that the device shown herein is extremely simple in construction and most efficiently used. When it is considered that bobby pins are generally used for pinning up a large number of curls, usually an extensive operation performed late at night and dozens of the pins are used in the operation, any device which will facilitate speed in the operation will be a great help to the user. The extreme simplicity of this device should therefore appeal to the users.

While the drawing shows four pockets for the pins, it should be understood that any number of

pockets may be employed, and that the particular configuration of the receptacle may be varied, provided it at least has a firm base and that any pocket shall firmly hold the funnel against rocking movement when the funnel is being used as a spreader.

While it is apparent that certain features of the invention are essential, it should be understood that some modifications may be made in the invention without departing from the principles of this invention, and it is, therefore, not the purpose to limit the patent granted hereon otherwise than necessitated by the scope of the appended claims.

I claim as my invention:

1. A bobby pin receptacle comprising a base member having a plurality of identically shaped vertically extending pockets whose upper ends are open, and a symmetrical funnel shaped device having its lower end portion held snugly and non-rockably in the upper end portion of one of said pockets and adapted to be removably insertable into and similarly held in any of the other pockets, said funnel having an upper radially flared portion terminating in an edge portion inclined at about a 45° angle, the upper edge of which is thin enough to enter between the prongs of a closed bobby pin when the latter is held vertically and thrust downwardly against said edge.

2. A bobby pin receptacle comprising a base member having a plurality of identically shaped vertically extending pockets whose upper ends are open, said pockets being proportioned to support bobby pins vertically with their upper ends protruding from the pockets, and a symmetrical funnel shaped device having its lower end portion held snugly and non-rockably in the upper end portion of one of said pockets and adapted to be removably insertable into and similarly held in any of the other pockets, said funnel having an upper radially flared portion terminating in an edge portion inclined at about a 45° angle, the upper edge of which is thin enough to enter between the prongs of a closed bobby pin when the latter is held vertically and thrust downwardly against said edge.

DEVONA A. BRUNNER.
